UNITED STATES PATENT OFFICE.

CHRISTIAN HAMILTON GRAY, OF LONDON, ENGLAND.

MEANS FOR VULCANIZING ARTICLES IN FLUIDS.

Application filed June 17, 1924. Serial No. 720,562.

To all whom it may concern:

Be it known that I, CHRISTIAN HAMILTON GRAY, a subject of the King of England, residing at London, England, have invented 5 certain new and useful Improvements in Means for Vulcanizing Articles in Fluids, of which the following is a specification.

This invention is for improvements in or relating to means for vulcanizing hollow 10 articles in fluids and has for its object to obtain a more homogeneous product than has heretofore been possible when vulcanizing articles of considerable size in fluids.

A roll such as is used for paper making 15 comprises a hollow cylindrical metal shell to the surface of which a layer of rubber is attached through the medium of a layer of ebonite.

It is essential that the rubber on these 20 rolls should be vulcanized to the same degree throughout, in order that its resulting resilience and strength should be uniform.

It is the practice to vulcanize these articles 25 in a horizontal position in a vessel containing a fluid which is heated to bring it to vulcanizing temperature.

When the said articles are vulcanized in a 30 fluid which is a bad conductor of heat (as for example water) it is found that the temperature of the fluid in the interior of the article does not rise with the temperature of the fluid exterior to the article, which results in the temperature of the metal shell of the roll rising much more 35 quickly at the ends than at the center and consequently the portion of the covering adjacent the metal shell being vulcanized to a greater degree at the ends than at the center of the roll.

According to one feature of this invention, there is combined with means for so carrying the article within the fluid-containing vulcanizing chamber that it can be 40 rotated therein, of means, such as scoops, secured to the article or a part carrying the same in such manner as to be operative to circulate the fluid through the interior of the latter as it rotates.

Another feature of this invention is the 45 method of vulcanizing hollow articles in a fluid-containing vulcanizing chamber consisting in circulating the fluid through the interior of the said article.

In the accompanying drawings which il-

lustrate one method of carrying out this invention— 55

Figure 1 is a central longitudinal vertical section through apparatus constructed according to this invention,

Figure 2 is an external view of a paper-roll 60 showing a detail not illustrated in Figure 1, and

Figure 3 is an end view of the part shown in Figure 2.

In the drawings the article to be treated is illustrated as a paper-roll A having a rubber layer A¹ attached to the roll by an ebonite layer A². These two layers A¹, A² are to be vulcanized and in the description are treated as part of the article A. The 70 container comprises a cylindrical chamber B surrounded by a jacket C. The interior of the jacket is supplied, by means not indicated, with the heating medium for vulcanizing, which may be steam. 75

At one end of the container is an inlet B¹ for fluid, and opposite this is an outlet B². This same end is provided with a detachable cover B³ wherein is mounted a driving-spindle D. The driving-spindle extends 80 through a stuffing-box D¹ in the cover. At its outer end it carries a pulley D², whereby it may be driven, and at its inner end it has a driving cross-arm D³.

The paper-roll is ordinarily carried on a 85 shaft E and this, for the purpose of vulcanizing, is supported in brackets E¹ which afford bearings wherein it can rotate. The brackets are mounted on a trolley F and this runs on guide-rails G within the container. A driving-head E² is attached to the shaft E at that end near the cover B³ of the container, and two pins E³ extend from the driving-head to engage the cross-arm D³ of the spindle D. 90

These paper-rolls are ordinarily provided with end-openings A³, and for the purpose of this invention these are taken advantage of to insert therein scoops H whose open ends face in opposite directions, that is, one in the direction of rotation and the other in the reverse direction. 100

The guide-rails G enable the paper-roll to be easily brought into proper position within the vulcanizing chamber B with the driving-head E² of the shaft E in proper position for engaging the cross-arm D³ of the spindle D. When the cover-plate B³ is 105

in position, the vulcanizing chamber is filled with a fluid, which may be water, and a heating medium, such as steam, is introduced into the surrounding jacket C. The 5 spindle D is then set in motion so that the roll is rotated in the chamber. As the open mouth of the leading scoop H advances through the water, water will be driven in thereat, and the trailing one will permit 10 water to escape therefrom so that a circulation of water will be maintained through the interior of the roll. This circulation of liquid through the roll is found to effect a more even vulcanization of the rubber 15 towards the inner portion of the mass of rubber than has heretofore been possible.

Vanес may be provided on the article if desired to circulate the water round the container exterior to the article. A vane suitable for this purpose is illustrated at J, Figures 2 and 3. The vane is carried by radial arms J¹ secured on the shaft E and is made in form to correspond to a quick-thread screw so that, as the roll A rotates, the water or 20 other fluid within the container will be propelled in the endwise direction of the container, as well as having imparted to it a rotary movement about the axis of the shaft E. More than one vane may be employed, 25 if desired, and it is not necessary that these should extend from one end of the roll to the other, although the vane J is shown so arranged.

Obviously, the invention is not restricted 30 to the vulcanizing of paper-making rolls, as it is applicable to any article which can be rotated, and can be made hollow and have communication with the exterior for the purpose of circulating the water through them.

40 The invention is not restricted to the use of liquid as the medium for conveying the heat in the jacket to the article, but it is applicable also to the use of a gas, such as air, for this purpose.

45 Where the article is not provided with end-holes through which the liquid could be circulated, these may be specially provided, and some articles which have heretofore been made solid might preferably be made hollow 50 for the purpose of getting an even distribution of heat through the same during vulcanization.

I claim:—

55 1. In apparatus for vulcanizing a hollow article in a fluid, the combination of a vulcanizing chamber to contain the fluid, supporting means for rotatably mounting the article in said chamber, and fluid-circulating means movable with the article and arranged 60 to circulate the fluid through the interior of the article as the article is rotated, substantially as described.

65 2. In apparatus for vulcanizing in a fluid a hollow article having openings in its wall, the combination of a vulcanizing chamber

for the fluid, supporting means for rotatably mounting the article in said chamber, and scoops movable with the article and arranged to circulate the fluid by way of said openings through the interior of the article as the 70 article is rotated, substantially as described.

3. In apparatus for vulcanizing a hollow article in a fluid, the combination of a vulcanizing chamber to contain the fluid, supporting means for rotatably mounting the 75 article in the chamber, a driving-spindle extending through one wall of the chamber, means for operatively connecting the driving-spindle within the chamber to the article, and fluid-circulating means movable with 80 the article and arranged to circulate the fluid through the interior of the article as the article is rotated, substantially as described.

4. In apparatus for vulcanizing a hollow article in a fluid, the combination of a vulcanizing chamber to contain the fluid, a hollow article of elongated form having orifices in its end-portions rotatably mounted in said chamber, and fluid-circulating means rotatable with the article and arranged to circulate the fluid through the interior of the article by way of the aforesaid orifices as the 85 article is rotated, substantially as described. 90

5. In vulcanizing apparatus, the combination of a vulcanizing chamber for a fluid, a hollow article of elongated form to be vulcanized having orifices in its end-portions rotatably mounted in said chamber, a driving spindle extending through one wall of 95 the chamber, means operatively connecting the driving spindle within the chamber to said article, and fluid-circulating means rotatable with the article and arranged to circulate the fluid through the interior of the article by way of said orifices as the article 100 is rotated, substantially as described.

6. In apparatus for vulcanizing a hollow article in a fluid, the combination of a vulcanizing chamber to contain the fluid, supporting means for rotatably mounting the article in said chamber, fluid-circulating means movable with the article and arranged to circulate the fluid through the interior of the article as the article is rotated, and means 110 rotatable with the article and arranged to impart movement to the fluid within the chamber about the exterior surface of the article as the article is rotated, substantially 115 as described.

7. In vulcanizing apparatus, the combination of a vulcanizing chamber for a fluid, a hollow article of elongated form to be vulcanized having orifices in its end-portions rotatably mounted in said chamber, fluid-circulating means rotatable with the article and arranged to circulate the fluid through the interior of the article by way of said orifices as the article is rotated, and means rotatable with the article to impart 120 movement to the fluid within the chamber 125 130

about the exterior surface of the article as the article is rotated, substantially as described.

8. In vulcanizing apparatus, the combination of a vulcanizing chamber for a fluid, a hollow article of elongated form to be vulcanized having orifices in its end-portions rotatably mounted in said chamber, fluid-circulating means rotatable with the article and arranged to circulate the fluid through the interior of the article by way of said orifices as the article is rotated, and a vane carried on the circumferential surface of the article and arranged to impart movement to the fluid within the chamber about the exterior surface of the article as the article is rotated, substantially as described.

9. In apparatus for vulcanizing a hollow article in a fluid, the combination of a vulcanizing chamber to contain the fluid, supporting means for rotatably mounting the article in the chamber, a driving-spindle extending through one wall of the chamber, means for operatively connecting the driving-spindle within the chamber to the article, fluid-circulating means movable with the article and arranged to circulate the fluid through the interior of the article as the article is rotated, and means rotatable with the article and arranged to impart movement to the fluid within the container about the exterior surface of the article as the article is rotated, substantially as described.

10. In apparatus for vulcanizing in a fluid a hollow article having orifices in its wall, the combination of a vulcanizing chamber for the fluid, supporting means for rotatably mounting the article in the chamber, a driving spindle extending through one wall of the chamber, means for operatively connecting the driving spindle within the chamber to said article, scoops movable with the article and arranged to circulate the fluid through the interior of the article by way of said orifices as the article is rotated, and a vane rotatable with the article and arranged to impart movement to the fluid

within the container about the exterior surface of the article as the article is rotated, substantially as described.

11. In apparatus for vulcanizing a hollow article in a fluid, the combination of a vulcanizing chamber to contain the fluid, a hollow article of elongated form having orifices in its end-portions rotatably mounted in said chamber, fluid-circulating means rotatable with the article and arranged to circulate the fluid through the interior of the article by way of the aforesaid orifices as the article is rotated, and means rotatable with the article and arranged to impart movement to the fluid within the container about the exterior surface of the article as the article is rotated, substantially as described.

12. In vulcanizing apparatus, the combination of a vulcanizing chamber for a fluid, a cylindrical paper-making roll having orifices in its end-portions rotatably mounted in said chamber, fluid-circulating means rotatable with said roll and arranged to circulate the fluid through the interior of said roll by way of the said orifices as the roll is rotated, and means rotatable with the roll and arranged to impart movement to the fluid within the container about the exterior surface of the roll as the roll is rotated, substantially as described.

13. In vulcanizing apparatus, the combination of a vulcanizing chamber for a fluid, a cylindrical paper-making roll having orifices in its end-portions rotatably mounted in said chamber, scoops carried in said orifices and arranged to circulate the fluid through the interior of the roll as the same is rotated, and a vane carried on the circumferential surface of the roll and arranged to impart movement to the fluid within the container about the exterior surface of the roll as the latter is rotated, substantially as described.

In testimony whereof I have signed my name to this specification.

CHRISTIAN HAMILTON GRAY.
